CONVERTIBLE GAME TABLE

Gary A. Gerber, Weston, and Melvin Zimmers, Westport,
Conn., assignors to Coleco Industries, Inc., Hartford,
Conn.

Filed Aug. 8, 1973, Ser. No. 386,598

Term of patent 14 years

Int. Cl. D6—03

U.S. Cl. D6—27

FIG. 1

FIG. 2

FIG. 3

FIG. 4

FIG. 5

FIG.6

FIG. 8

FIG. 7

FIG.9

FIG.10

FIG. 1 is a perspective view of a convertible game table showing our new design;

FIG. 2 is a side elevational view thereof, the elevational view of the opposite side being essentially the same;

FIG. 3 is an end elevational view thereof, the elevational view of the opposite side being essentially the same;

FIG. 4 is a plan view thereof;

FIG. 5 is a bottom view thereof;

FIG. 6 is a plan view thereof with the removable top reversed from the position shown in FIGS. 1-4;

FIG. 7 is a plan view thereof with the removable top removed in its entirety;

FIG. 8 is a fragmentary elevational view similar to FIG. 2 with the ball boxes moved to the alternate position thereof;

FIG. 9 is a sectional view along the line 9—9 of FIG. 6; and

FIG. 10 is a fragmentary sectional view along the line 10—10 of FIG. 7.

We claim:

An ornamental design for a convertible game table, as shown and described.
